L. D. HAWKINS.

Rice Cleaner.

No. 33,064.

Patented Aug. 13, 1861.

UNITED STATES PATENT OFFICE.

L. D. HAWKINS, OF SAN FRANCISCO, CALIFORNIA, ASSIGNOR TO ALFRED PEABODY, OF SALEM, MASSACHUSETTS.

MACHINE FOR SCOURING, CLEANING, AND SMUTTING RICE, COFFEE, AND OTHER GRAINS.

Specification of Letters Patent No. 33,064, dated August 13, 1861.

To all whom it may concern:

Be it known that I, L. D. HAWKINS, of San Francisco, California, have invented a new and Improved Machine for Cleaning 5 Rice, Coffee, and other Grains and for Smutting Wheat, and that the following is a full and exact description of the same.

My invention consists in the use of a drum or cylinder, covered with strips of sheep 10 skin with the wool on them for cleaning rice and other grains, and with strips of sheet iron or other like substance for smutting wheat, revolving rapidly inside of a hollow cylinder composed of alternate perpendicular 15 stone blocks and frames of wood or iron covered with wire cloth, adjusted and used as hereinafter set forth.

The grain to be cleaned is introduced into the machine at the top and passing down 20 through the space between the drum and the outer cylinder it is thrown with great rapidity against the surface formed by the stones and the wire cloth, by which the grain is severely rubbed against the said surface 25 so as to break and peel off the skin or hull which is on it, without pulverizing or breaking the grain itself, and at the same time the substance scraped or rubbed from the grain is thrown out through the wire cloth, 30 which keeps the stones free from the meal and dirt and the grain comes in direct contact with them during its passage through the machine.

To enable others skilled in the art to make 35 and use my invention, I will proceed to describe the same with reference to the accompanying drawings, in which—

Figure 1. represents a perspective view of the machine. Fig. 2. represents a horizontal 40 section, and Fig. 3. represents a vertical section taken through the red lines $\alpha\alpha$ of Fig. 2.

Similar letters of reference where they occur in the separate figures, denote like parts 45 of the apparatus, in all the figures.

The base A of the machine, and the upper plate B, I propose to make of cast iron, and to unite them by hollow cast iron columns C, through which rods a, pass, and these rods 50 may also pass through the floor of the building to hold all firmly together and to the floor. The chink pieces D, are of wood, and their inner sides next the drum are covered with sheep skin to prevent the wearing away 55 of the wood, as well as to make a tight joint,

between them, and the stone, and screen frame next to them. These chink-pieces may be adjustable through set screws in the bed and top plate, that they may be set to, or from the cylinder, as may be required. 60

E, E, are stone segments radially arranged on the base and top plate, and F, F, are gauze screens also radially arranged upon said bed and top plate and interposed between the stone segments, so that the stone 65 segments E, screens or screen frames F, and chink pieces D, form the outer case of the machine.

G, is a shaft supported in the bridge trees H, I, at the top and bottom, and having upon 70 its upper end a pulley J, around which the belt that is to drive it passes. Upon this shaft is placed a drum or cylinder K, the perimeter of which is covered with sheep skin b, having the wool upon it—or pelts, as 75 they are termed. This cylinder with its covering should be large enough to run in close proximity to the inner edges of the stone segments, screens, and chink pieces.

The stone segments E, at their lower ends 80 rest in shoes L, and by means of a set screw c, these shoes, together with their stone segment may be moved to or from the cylinder K, to properly adjust their working surfaces to each other. And a set screw d, which 85 presses against the stone segments at their tops, holds them to the cylinder at that point. For the purpose of removing or replacing the segments E, the shoe L, has a sliding cleat or ledge e which can be removed, and 90 the segment will then slide out; and when this ledge is replaced it holds the segment to the shoe.

The screen frames F, are also adjustable; they rest at their base in shoes M, which can 95 be moved toward or from the cylinder, by set screws f, and their tops are adjusted and held up to the cylinder by other set screws g, which, like those d, above mentioned for adjusting the stone segments, pass through lugs 100 h, h, said lugs being made removable, so that the segments, as well as the screen frames may be removed and replaced when required.

The outer case opposite to the screens F, as shown more distinctly in Fig. 1, is open 105 so that the dust and other scurings from the grains may pass out of the case; and thus the alternate scouring or polishing surfaces of the stone segments, and intervening screens, make one operation as it were, of the 110

hulling and polishing, and the separation of the impurities from the cleaned grains, and saves an after separation, as is now practiced.

5 To prepare this machine, especially for smutting wheat, I propose to use instead of the sheep skin covering, strips of metal, running up and down the cylinder, and at an angle sufficient to form a kind of conveyer to 10 hurry the wheat through. But for rice, coffee, and such like grains, the construction above set forth is that which I design to use.

In the machine represented in the drawing there are four stones and four frames, but 15 any number from two of each upward may be used, the number depending upon the size of the machine required.

I do not claim the revolving drum covered with sheep skins or other substances, nor the 20 stones, nor the frames covered with wire cloth, as my invention; but

I claim as my invention and desire to secure by Letters Patent,

1. The combination of the stones E, E and 25 wire cloth covered frames F, F, whereby the pulverized skin and dirt from the surface of

the grain is thrown out, leaving the stones free to act on the grain, and whereby the action of a cleaner and polisher are combined, thus in most cases doing away with the use 30 of wire polishers as a supplementary process, and in all cases materially lightening the work to be done thereby.

2. The adjustment of the wire polisher frames to be moved up toward or drawn back 35 from the revolving drum simultaneously with the stones.

3. The use of the iron shoes or slides L, M, upon which the stones and frames are placed, in combination with the cast iron bed plate 40 A, and the screws e, f, whereby the size of the hollow cylinder composed of the stones and frames may be increased or lessened as desired.

In testimony whereof I have signed my 45 name to this specification in the presence of two subscribing witnesses.

L. D. HAWKINS.
